UNITED STATES PATENT OFFICE.

ALPHEUS O. HURXTHAL, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DRIER.

Application filed April 23, 1927. Serial No. 187,215.

My invention relates to certain improvements in driers of the type in which the material is mounted on trucks.

The invention is particularly adapted for 5 drying articles such as hats, but it will be understood that the invention can be used for drying other articles without departing from the essential features of the invention.

One object of the invention is to provide a 10 drier in which there are two trucks, so that one can be loaded while the other is in the drying chamber.

A further object of the invention is to so 15 construct the trucks that when one is within the drying chamber, the ends of the truck will close both ends of said chamber, dispensing with the independent doors for the drier.

A still further object of the invention is to 20 so design the truck that the poles for supporting the hats may be hung from overhead bars.

In the accompanying drawings:

Fig. 1 is a plan view of my improved truck drier;

25 Fig. 2 is a side view;

Fig. 3 is an end view;

Fig. 4 is an enlarged longitudinal sectional view through the drying chamber, showing a truck in position;

30 Fig. 5 is a perspective view of one of the trucks, showing the poles in position without the pegs to avoid confusion; and

Fig. 6 is a view of one of the poles for carrying the hats.

35 Referring to the drawings, 1 is a drier which is substantially the length of one of the trucks 2. The casing of the drier encloses a drying chamber and two circulating chambers in the present instance. The

40 drawings show a double drier having a wide drying chamber and two trucks, with two trucks for each track, but it will be understood that a drier having a single track may be used in some instances.

45 The rails 3 of the tracks extend through the drying chamber and beyond each end of the drier as shown, so as to support a truck being loaded or unloaded. The rails are arranged overhead in the present instance, and

50 have stop bars 18 at their outer ends which connect the rails, the trucks being suspended from the rails. Each truck has axles 6 mounted in suitable bearings, and on each axle is a flanged wheel 5, which travels on the rails of the track.

Each truck is closed at each end by solid end sections 7 and 8, which close the ends of the drying chamber when a truck is within the chamber. The end 7 snugly fits the end opening in the drier, while the end 8 is 60 larger than the opening and fits against the end of the drier and acts as a stop for the truck as well as a closure for that end of the drying chamber. By this arrangement, no doors are required for the drying chamber, 65 as the two ends of the truck close the drying chamber sufficiently to prevent the escape of the air in circulation.

Each truck is made in the form of a skeleton frame 4. The end sections 7 and 8 of the 70 truck are suspended from the frame 4 and are connected at their lower ends by rods 17. A series of bars 9 extend across the frame 4 from which the poles 10 are suspended. Each pole in the present instance is made as 75 shown in Fig. 6, and has a hook 11 which is shaped to engage one of the cross-bars 9, while projecting from the pole are a series of diagonal pegs 12 on which the hats are mounted. These pegs may have enlarged ends, as shown 80 in Fig. 6, covered with felt or other suitable material if found desirable.

At each side of the drying chambers are circulating chambers 13, and located in the chambers in the present instance are circulating fans 14, the casings of which are made as 85 shown in Fig. 2. These fans are driven by belting from a motor 15. In the present instance there are two fans at each side of the drying chamber and an independent motor 90 drives each pair of fans. 16 are heating coils located in the circulating chamber and are arranged to heat the air in circulation.

The operation is as follows:—When one of the trucks is on the rails at one side of the 95 drier, the hats are placed on the poles 10 and the poles are hung from the cross-bars 6. When the truck is loaded with poles and the hats on the other truck within the drier have been dried, and are ready to be removed, the 100 truck within the drier is withdrawn from the drying chamber and the other truck carrying the hats to be dried is run into the drying chamber, the two ends of the truck closing the drying chamber. The large end of the truck 105 also acts as a stop to locate the truck within the drier, the drier being closed at both ends, and where a double drier is used as in Fig. 1, two trucks are located side by side within the drying chamber of the drier. The heated air 110

in circulation will dry the hats or other articles suspended from the bars of the trucks.

A drier of this type occupies very little floor space. The trucks can be readily loaded and unloaded while the articles on the other truck are being dried.

I claim:

1. The combination in a drier having a drying chamber; means for circulating heated air 10 in the drying chamber; two overhead rails extending through the drying chamber and beyond each end thereof; and two independent trucks mounted on the rails, said trucks having means by which material to be dried is 15 suspended therefrom, each truck having solid ends, one end being larger than the other so that the smaller end will fit the opening in the drier at one end, while the other will fit 20 against the end of the drier at the opposite end and limit the movement of the truck.

2. The combination in a drier having a drying chamber; a circulating chamber at each side of the drying chamber; means for circulating air in said chambers; overhead rails extending through the drying chamber and beyond each end thereof; two independent trucks mounted on each pair of said rails, the trucks having closed ends, one end of each truck being larger than the opposite end, the smaller end extending within the opening of the drying chamber and the larger end resting against the end of the drying chamber when the truck is within the said chamber; a series of cross-bars on each truck; hooked poles arranged to engage the cross-bars and 30 to be suspended therefrom; and pegs on the poles on which articles to be dried are mounted.

ALPHEUS O. HURXTHAL.
